VOTING MACHINE

Richard D. Uhthoff, Cresskill, N. J., assignor of one-tenth to Benjamin Webster and nine-twentieths to Thomas A. Dobson, both of New York, N. Y.; Frieda M. Uhthoff administratrix of said Richard D. Uhthoff, deceased

Application December 18, 1929
Serial No. 414,929

8 Claims. (Cl. 101—96)

This invention relates to voting machines and more particularly to that type in which a register tallies the number of votes cast on each voting knob.

5 It has for its objects, among others: First, to provide a simple, certain, and robust mechanism for printing a record of the vote registers; second, to provide such a device that may be operated by a quick, simple motion external to the machine; third, to make the record complete and positive in every detail; and fourth, to make improvements in the devices by which the foregoing objects are attained.

Reference is made to the drawings which are 15 hereby made a part of this specification, in which

Figure 1 is a side elevation with a part broken out, the roll in printing position,

Figure 2 is a view similar to Figure 1 showing the upper roll illustrated in Figure 1 and two 20 more rolls which are broken out in Figure 1, the rolls in nonprinting position,

Figure 3 is a rear elevation of one of the rolls and the adjacent roll in part broken away in non-printing position with reference to the vote registers,

25 Figure 4 is a view similar to Figure 3 with other parts broken away at the right, and

Figure 5 illustrates one of the flexible joints in the roll-supporting shaft.

30 Similar numerals of reference refer to like parts throughout the specification. A horizontal round bar or rod 1 supports a horizontal row of rollers 2 each of which is covered with a rubber pressure face or plate 3. Transverse slots 4 elongated horizontally in the vertical bars 5 support the rod 1 movably to and from the vote registers 16. A stud 6 projects transversely from the horizontal bracket 7 and is adapted to travel in the vertical eccentrically formed slot 8 at the top of each vertical bar 5. The slot 8 is so formed that as the vertical bar 5 is raised the stud 6 travels in an inclined portion the length of which is sufficient to carry the bar toward the vote registers 16 a distance equivalent to the distance of the pressure rolls 3 from the faces of the vote registers in their nonprinting position. The slot 8 is then continued in a downward straight portion of a length sufficient to permit the pressure rolls to roll completely over the faces of the numerals 3 on the vote registers. The slot is then continued in another inclined portion to carry the printing rolls away from the registers. Upon reversing the action to lower the vertical bars 5 again it is obvious that the pressure rolls are again pressed

35 over the entire faces of the numerals of the vot- 40 45 50 55 60 65 70 75 80 85 90 95 100 105 110

ing registers which gives double assurance of a printed record. A vertical toothed rack 9 is secured to the lower portion of each vertical bar 5 to provide a means for vertical reciprocation of the bars as will be more particularly described hereinafter. The bar 5 is prevented from transverse or endwise movement by two brackets 10 one of which is mounted on each side of the vertical bar and connected to the lower end of a vertical angled strip 11 at one end and at the other to the pedestal 12 which is in turn fastened to the base of the machine. The strips 11 are mounted in pairs as clearly shown in Figures 3 and 4 with the right-angled strip 13 turned in the opposite direction in each pair and each pair has journaled therein a roller 14 above and adjacent a projection 15, a series of which is formed on the vertical bar 5. The form of the projection 15 is like that of the slot 8. That is, it has two similarly angled surfaces terminating in a vertically planed surface, the inclined surfaces being of similar length and of a length sufficient to carry the pressure rolls 2 from the nonprinting position into engagement with the surfaces of the numerals of the vote registers. When the vertical bar 5 is raised the upper inclined surface of projection 15 engages roller 14 which forces the bar toward the vote registers 16. After the pressure rolls 2 are in engagement with the faces of the vote registers the rolls 14 travel over the vertical plane surfaces of the projections thus affording a complete printing record from bottom to top and the lower inclined surfaces permit the vertical bar to again travel away. When, however, the vertical bars are again lowered the printing rolls are again carried toward the vote registers and roll down over the entire faces of the numerals from top to bottom and again are carried away into the nonprinting position. By means of this device there is a positive printing operation initially, a continued upward impression over the entire faces of the numerals on the vote registers and a second positive impression made in the opposite direction thus assuring a perfect vote record from each and every register, the mechanism thus assuring positive and definite impressions at all times. Mounted on each side of the vertical bar 5 and overlying each slot 4 to the rear of rod 1 is a spring 17 fastened at the lower end in a slit stud 18, bent back of the rod 1 and at its upper end passed in front of the pin 19. These springs provide for wear or any irregularities in the surfaces of the pressure rolls and make a spring-pressed contact between the rubber faces 3 and the numerals of the vote

registers 16. Suitable rolls support the paper strip 20 and the inking strip 21 which are passed down over the faces of the numerals of the vote registers 16. The vertical bars are raised and lowered by means of an eccentrically mounted gear wheel 22 whose teeth are adapted to mesh with the teeth of gear rack 9. The teeth are so assembled that when the vertical bars are in the printing position the teeth on the wheel are those nearest the center and when the printing rolls are in the nonprinting position the gear teeth most remote from the center are in engagement with the rack. The eccentricity of the gear wheel 22 is proportioned to the distance between the bars in the nonprinting position and the vote registers. A crank 23 is connected with a shaft passed through the side wall of the machine so that the printing operation is completed without access to the mechanism of the machine. The rods 1 are provided at a point adjacent the center of each vertical bar each with a flexible joint formed by the convex protuberance 24 on one section of the rod 1 and a symmetrical concavity 25 in the adjacent section of the rod 1, as shown in Figs. 3 and 5. There are two vote registers 16 between each pair of vertical bars 5 and the roller 1 which overlies each pair is mounted on a separate section of the rod 1 and is under resilient pressure from the springs 17 on the adjacent vertical bars 5, whereby a uniform printing pressure is applied on all the vote registers 16 of the machine. The strip 26 shown in section is the vertical strip usually employed to support the voting registers at the rear of the voting machine of the manually operated type in which there is a series of voting knobs. It is obvious that the various units employed in my invention can be increased or decreased in number to provide for any desired number of vote registers and that many modifications may be made in the details of my invention of which I have illustrated and described a preferred embodiment, and therefore I do not choose to limit myself except as in the appended claims.

45 I claim:

1. In a voting machine provided with a series of vote registers, a shaft adjacent a register, a pressure roll on said shaft, vertical bars on which said shaft is mounted, means for moving said bars toward said register, and means comprising a rack and a toothed wheel eccentrically mounted for lifting said bars.
2. In a voting machine provided with a series of vote registers, a shaft adjacent a register, a pressure roll mounted on said shaft, a vertical bar on which said shaft is mounted, means for moving said vertical bar toward and away from said register comprising a slot and stud and a roller and an inclined surface, a rack on the lower portion of said bar, a toothed wheel

adapted to engage this rack, and a crank externally mounted with reference to the voting machine and connected with said toothed wheel.

3. In a voting machine provided with horizontal and vertical rows of vote registers, shafts horizontally mounted adjacent horizontal rows of registers, a series of vertical bars on which said shafts are mounted, a series of pressure rolls rotatably mounted on said shafts adjacent said horizontal row of registers, said vertical bars and said pressure rolls being mounted with bars between the rolls and means for moving said bars toward and away from said vote registers adapted to be operated externally to the machine.

4. In a voting machine provided with a series of vote registers in horizontal rows, a series of pressure rolls adapted to engage the vote registers in a horizontal row, a shaft on which said pressure rolls are mounted comprising flexible joints, and means for moving said pressure rolls toward and across said row of vote registers and away from said row of vote registers, comprising a plurality of slots having each a central portion and a proximate inclined portion on either side merging into a vertical portion.

5. In a voting machine provided with horizontal and vertical rows of vote registers, horizontal shafts adjacent the horizontal rows of registers, pressure rolls on said shafts, vertical bars in which said shaft are rotatably mounted, and means for pressing said bars toward said registers comprising studs traveling in inclined slots.

6. In a voting machine provided with horizontal and vertical rows of vote registers, horizontal shafts adjacent the horizontal rows of registers, pressure rolls on said shafts, vertical bars on which said shafts are rotatably mounted, and means for pressing said bars toward said registers comprising studs traveling in inclined slots and rolls bearing on inclined surfaces.

7. In a voting machine provided with horizontal and vertical rows of vote registers, horizontal shafts adjacent the horizontal rows of registers, pressure rolls on said shafts, vertical bars on which said shafts are mounted, and means for pressing said bars toward said registers comprising inclined surfaces and rollers.

8. In a voting machine provided with horizontal and vertical rows of vote registers, horizontal shafts adjacent the horizontal rows of registers, pressure rolls on said shafts, vertical bars on which said shafts are mounted, means for moving the upper portions of said bars toward said registers, and means comprising an eccentrically mounted member for lifting said bars.

RICHARD D. UHTHOFF.
